UNITED STATES PATENT OFFICE.

OSCAR J. HOLMES, OF CHICAGO, ILLINOIS, ASSIGNOR TO ATLAS EDUCATIONAL FILM CO., OF CHICAGO, ILLINOIS, A CORPORATION OF ILLINOIS.

FILM AND SPROCKET-DRUM.

1,144,414.

Specification of Letters Patent. Patented June 29, 1915.

Application filed April 5, 1915. Serial No. 19,140.

To all whom it may concern:

Be it known that I, OSCAR J. HOLMES, a citizen of the United States of America, and a resident of Chicago, in the county of Cook, 5 State of Illinois, have invented certain new and useful Improvements in Films and Sprocket-Drums, of which the following is a specification.

This invention relates to that class of moving picture mechanisms in which a sprocket drum is employed to positively feed the pictured film through the mechanism. And the present improvement has for its object to provide a simple and efficient structural formation of the sprocket perforations in the pictured film or web, and the coacting sprocket teeth of the film feeding drum, and with which the surreptitious use of an ordinary inflammable film having standard 10 sprocket perforations is prevented, and which on the other hand admits of a non-inflammable film of the present formation in the ordinary moving picture mechanisms having a standard formation of their film 15 feeding sprocket drums, all as will herein-after more fully appear.

In the accompanying drawings:—Figure 1, is a detail sectional elevation of a sprocket drum and a fragment of a moving picture film, illustrating the preferred form of the present invention, the film being shown in section. Fig. 2, is a rear elevation of the same. Fig. 3, is a view similar to Fig. 1, showing a modification. Fig. 4, is a rear 30 elevation of the same.

Similar reference numerals indicate like parts in the several views.

In the use of moving picture exhibitions for educational and like purposes in school 40 rooms and the like, it is necessary that a non-inflammable and safe film be used and the surreptitious use of an inflammable and dangerous film be prevented. And an additional requirement from a commercial stand-point is that such non-inflammable and safe film is capable of use in connection with a standard form of film feeding sprocket drum of an ordinary moving picture mechanism, and to the above ends the present invention comprises a structural formation 45 and association of parts as follows:

Referring to Figs. 1 and 2, a sprocket drum designated as 5 has formed on its periphery a plurality of alternating sprocket teeth 6 and 7, with the series of sprocket

teeth 6 of the standard size and spacing, while the series of sprocket teeth 7 are of the standard spacing but are made of a larger size or extent, preferably by being increased both in height and in one direction 60 from the imaginary uniform radial spacing lines of the plurality of sprocket teeth. 8 designates a portion of the companion moving picture film or web formed with the corresponding plurality of alternating sprocket perforations 9 and 10, with the series of perforations 9 of the standard size and spacing, while the series of perforations 10 have the standard spacing but are made of a larger size or extent, and preferably by being increased in length in one direction 65 from the imaginary spacing lines of the plurality of perforations.

In the construction illustrated in Figs. 3 and 4, the entire plurality of sprocket teeth 6' on the periphery of the sprocket drum 5 are of a standard size and spacing, with alternate pairs of said sprocket teeth connected together by intermediate webs 7', which are adapted to perform the functions of the enlarged sprocket teeth 7 heretofore described. And in connection with said formation shown in Figs. 3 and 4, the companion moving picture film 8' is formed with a corresponding series of sprocket perforations 9' of a standard size and spacing, and with alternate pairs of said perforations connected together by intermediate slits or passages 10' corresponding with and receiving the webs 7 aforesaid. 70

Having thus fully described, my said invention, what I claim as new and desire to secure by Letters Patent, is:—

1. A moving picture film formed with a series of sprocket perforations having a standard spacing with alternate perforations of the series having a greater extent, substantially as set forth. 75

2. A moving picture film formed with a series of sprocket perforations having a standard spacing with alternate perforations of the series having a greater extent in one direction from their normal central construction lines, substantially as set forth. 80

3. In a moving picture mechanism, the combination of a moving picture film formed with a series of sprocket perforations having a standard spacing with alternating perforations of the series having a greater extent, and a sprocket drum formed with a series of 85

sprocket teeth having a standard spacing with alternate teeth of the series having a greater extent, substantially as set forth.

4. In a moving picture mechanism, the combination of a moving picture film formed with a series of sprocket perforations having a standard spacing with alternating perforations of the series having a greater extent in one direction from their

normal construction lines, and a sprocket drum formed with a series of sprocket teeth having a standard spacing with alternate teeth of the series having a greater extent in one direction from their normal construction lines, substantially as set forth.

Signed at Chicago, Illinois, this 2nd day of April, 1915.

OSCAR J. HOLMES.
